United States Patent Office

Des. 197,285
Patented Jan. 7, 1964

197,285

BOOK BOX DESK

Herbert E. Williams, San Antonio, Tex., assignor to
American Desk Manufacturing Company, Temple,
Tex., a corporation of Texas

Filed Apr. 1, 1963, Ser. No. 74,241

Term of patent 14 years

(Cl. D33—11)

FIG 1

FIG.2

FIG.3

FIG.4

FIG.5

FIGURE 1 is a perspective view of a book box desk embodying my new design;

FIGURE 2 is a rear elevational view thereof;

FIGURE 3 is a front elevational view thereof;

FIGURE 4 is a side elevational view thereof; and

FIGURE 5 is a bottom plan view thereof.

The dominant features of my design reside in those portions shown in full lines on the drawing.

I claim:

The ornamental design for a book box desk, substantially as shown and described.
